UNITED STATES PATENT OFFICE.

C. L. INGRAHAM AND E. ROUNDS, OF BERLIN, WISCONSIN.

WASHING-MACHINE.

Specification of Letters Patent No. 28,180, dated May 8, 1860.

To all whom it may concern:

Be it known that we, C. L. INGRAHAM and EMORY ROUNDS, of Berlin, in the county of Green Lake and State of Wisconsin, have 5 invented certain new and useful Improvements in Washing-Machines; and we do hereby declare that the following is a full, clear, and exact description of the same, reference being had to the accompanying drawings and to the letters of reference marked 10 thereon.

The nature of our invention consists in the employment of a pump in connection with a washing box in which is placed an 15 open wheel substantially as set forth.

In the annexed drawings Figure 1 represents a side elevation Fig. 2 is a plan view Fig. 3 is a section through the pump Fig. 4 is a cross-section of the cylinder.

20 In the figures A, represents a wash box which may be constructed of any desired size, and in any known way. The shape which we prefer is square, with a concave bottom. Within this box is placed a cylinder which may be hexagonal, or octagon, or 25 any other desired. This cylinder has two solid heads, which are annular. Bars extend from one of these heads to the other, and slats are nailed to the bars, thus making 30 an open cylinder which will hold clothes but through which water may course backward and forward. Across one side of this box is secured a small water reservoir L, which connects with a pump, P, which is also 35 placed in the box. Water is pumped into this reservoir, from which it is forced through openings in its side into the cylinder B.

D, is a gear wheel to which a handle is

40 attached. Said wheel works into a wheel E, which revolves the cylinder B, and said wheel E, works into a wheel F, to which is attached a crank. A connecting bar H attaches or connects the crank G to the lever I, which serves to communicate motion to the pump rod J. When the handle of wheel D, is turned rotary motion is given to the cylinder B, in which the clothes are placed; motion is at the same time communicated to the pump rod. The pump draws water from 45 the box A, and drives it into the reservoir, from which it is expelled by the force of the pump, in small streams, through the slats on the cylinder B, and against the clothes in said cylinder, thus washing the dirt from 50 them as they revolve.

M, M, are bars placed across the cylinder to retard the motion of the clothes and to assist in turning them over.

Having thus fully described our invention what we claim as new and desire to secure by Letters Patent is

Not the pump or the wheel, separately, but the combination of the pump as arranged with the wheel or cylinder which has 60 a slatted or open periphery, the two being 65 so arranged and connected that the water will be raised from the box by the pump and injected, upon and among the clothes through the open periphery of the cylinder 70 as it revolves, substantially as herein specified.

C. L. INGRAHAM.
EMORY ROUNDS.
